UNITED STATES PATENT OFFICE.

WILLIAM BROWN, OF ST. LOUIS, MISSOURI.

DESIGN FOR A FAN.

57,816.

Specification for Design.

Patented May 10, 1921.

Application filed October 18, 1920. Serial No. 417,854. Term of patent 7 years.

To all whom it may concern:

Be it known that I, WILLIAM BROWN, a citizen of the United States, residing at the city of St. Louis, and State of Missouri, have invented a new, original, and ornamental Design for Fans, of which the following is a specification, reference being had to the accompanying drawings, forming part thereof.

In the drawings the figure is a front elevation of a fan showing my new design.

I claim:

The ornamental design for a fan, as shown.

WILLIAM BROWN.
